CORE FOR GLASS MOLDS

Raymond A. Senkbell, Baltimore, Md., assignor to
Maryland Glass Corporation, Baltimore, Md., a
corporation of Maryland

Application February 10, 1942, Serial No. 430,285

3 Claims. (Cl. 49—76)

This invention relates to cores for glass molds.

In glass-making machinery it has been proposed to provide a core which is adapted to be moved into the bottom of the mold for forming a pocket in the molten mass of glass which has been dropped into the mold while at the same time the core presses the molten glass into a matrix at the lower end of the mold for forming the neck of a bottle.

In order to prevent the glass from moving out of the mold when the core is forced therein, an integrally formed ring is located on the core so that it will be moved with the core into flat contact with the bottom face of the mold. However, the shell of the mold is formed of cast iron and due to the intensity of the heat which is radiated through the mold, said shell becomes quite brittle and when the solid mass of metal in the form of a ring is moved into engagement with the bottom of the mold simultaneously with the insertion of the integrally formed core, the impact is at times sufficiently great to crack or break parts of the mold.

It is an object of the present invention to provide a core and a cooperating ring which will prevent fracture of the mold or associated parts when the core is forced into an opening in the bottom of the mold, since the ring is slidably mounted on the outer wall of the core and movable relatively to the core so that when the core is moved into the mold the ring will likewise move upwardly but due to the cushioning effect of springs which support the ring on the base of the core pressure will be progressively increased on the ring while eliminating the usual jarring action of the ring against the bottom of the mold.

A further object of the invention is the provision of a core for glass molds in which a ring is slidably mounted on the core with a plurality of springs and rods for supporting the ring on the base of the core so that when the core is moved inwardly into the usual passage in the bottom of the core where the neck of the bottle is formed, said ring will be moved up and will lightly engage the bottom of the mold while continued movement of the core into the mold will cause the plurality of springs to exert a progressively increasing pressure on the ring and sufficient to hold the ring in place so that passage in the bottom of the mold will be closed by forming the neck of the bottle and holding the molten glass within the mold at the neck forming portion.

This invention will be best understood from a consideration of the following detailed description, in view of the accompanying drawing form-

ing a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in elevation of a core for glass molds shown in an inoperative position.

Figure 2 is a horizontal section taken along the line 2—2 of Fig. 1.

Figure 3 is a horizontal section taken along the line 3—3 of Fig. 1.

Figure 4 is a vertical section similar to that shown in Fig. 1, but disclosing the core and a cooperating movable ring in an operative position on the bottom of a mold.

Referring more particularly to the drawing, 10 designates the lower end of a mold for forming glass bottles which has a circular passage 11 in the lower end with an annular groove 12 to receive molten materials to provide an external rib on the outer surface of the neck of a bottle.

The sleeve 13 extends downwardly from the mold 10 and has a flared mouth 14 at its lower end. The sleeve 13 may be supported in any approved manner from the mold 10 and since this part forms no portion of the invention no details of the connection will be described.

In these types of machines the core is automatically moved into place in the passage 11 of the mold 10 by an arm which is not shown in the present construction. This arm is adapted to be moved upwardly for forcing the core into the passage at about the time the molten mass of glass is poured into the upper end of the mold. In other words, the core must be centered and must be in operative position within the mold to prevent the loss of molten glass from said mold.

A core 20 is provided with a reduced upper end as shown at 21, and this core is hollow as indicated at 22 throughout its length except that the extreme upper end of the core as shown at 23 is rounded and closes the hollow passage 22.

The core is provided with a base 25, which is cylindrical in shape and has a greater diameter than the body of the core 20. Said body is provided at its upper end with an annular groove 26 which forms an annular shoulder to receive the lower ends of coil springs 27 which are spaced around the core 20 at approximately 90 degrees apart. The body is also provided with a plurality of vertical passages 30 to receive rods 31 which have their upper ends as shown at 32 threaded into pockets in a ring 33. This ring is slidably

mounted on the core 20 at its lower end and where the core is substantially cylindrical.

The base 25 of the core is provided with pockets 35 which receive the heads 36 of the rods 31. Since the ring 33 is rigidly connected with the upper ends of the rods 31 said rods riding in the passages 30 will aid in centering the ring with respect to the cylindrical walls 40 of the member 13. Since the ring 33 neatly fits within the walls 40 the core 20 will likewise be centered with respect to the passage 11 in the mold 10.

The base 25 of the mold 20 is connected to an arm of a machine for automatically moving the core through the passage 11 into the hollow body of the mold 10. As the core is moved upwardly and the outer closed end 23 of the hollow core is moved into the passage 11 it will be centered with respect to the said passage by means of the ring 33 after it has moved through the flared passage 14 at the outer end of the sleeve 13 and after the outer walls of the ring have engaged the cylindrical walls 40 of the sleeve 13.

The core is moved upwardly and will continue to enter the passage 11 in the mold 10 until the upper face of the ring 33 engages the bottom of the mold 10. However, continued upward pressure on the base 25 of the core will cause the core to move upwardly into the mold while the progressively increasing pressure will be exerted on the coil springs 27 until the core and the ring 33 reach the positions shown in Fig. 4 with the springs 27 fully compressed. The ring is provided with a groove 45 adjacent the outer walls of the core 20 in order to provide a finish for the outer end of the neck 46 of the bottle which is being formed in the initial steps. Thus it will be seen that the ring not only closes that portion of the passage 11 which is spaced from the outer walls of the core 20, but it also aids in finishing the outer end of the bottle.

The base of the core is provided with a cylindrical portion 47 below the bottoms of the springs 27 and since this cylindrical portion has the same diameter as the external annular surface of the ring 30, it will also cooperate with the ring for guiding the core centrally of the passage 11.

Since the upper end of each spring 27 engages the shoulder 26 at the piston or cylindrical portion 47 these springs will be compressed between the shoulder 26 and the ring 30, but the cushioning of the ring on the springs will prevent the ring from coming into contact with the bottom of the mold in a sharp impact and thus the cushioning of the ring will prevent injury to the mold and likewise the ring will not be injured when it comes in contact with the bottom of the mold.

I claim:

1. In a molding apparatus, a core, a mold having an opening in the bottom thereof and a neck-forming chamber at the upper end, said core having a base portion of greater cross-sectional area than the core and providing a shoulder between the base portion and the core, said core having a diameter less than the neck-forming chamber to provide an annular space between the wall of the neck-forming chamber and the core when said core is projected through said neck-forming

chamber, a cylinder embracing the base portion and providing a slidable support for the base portion for centering the core in the mold, a ring movably mounted on the core, the inner wall of the mold being cylindrical for slidably receiving the ring, a plurality of rods slidably mounted in the base portion and rigidly connected with the ring, and a coil spring on each rod located between the ring and shoulder, said springs adapted to be compressed when the core is moved inwardly of the cylinder for forcing the ring against the bottom of the neck-forming portion of the mold.

2. In a molding apparatus, a cylindrical core, a mold having an open-ended chamber and a neck-forming chamber opening at its lower end into the first chamber, the first chamber having a greater cross-sectional area than the second chamber, the top of the first chamber forming a shoulder surrounding the lower open end of the second chamber, said core located in the first chamber and adapted to be moved into the neck-forming chamber, the core having a base portion of greater diameter than the core, thereby providing a shoulder between the core and base member, a cylinder embracing the base and providing a slidable support for said base portion for centering the core in the mold, a ring slideable on the core, with the outer periphery slidably received by the wall of the open-ended chamber, a plurality of rods having the inner ends thereof secured to the ring and a coil spring surrounding each rod and located between the second shoulder and the under face of the ring, said coil springs adapted to be compressed when the core is moved into the neck-forming chamber for forcing the ring against the first-mentioned shoulder, and cooperating with the core for closing the lower end of the neck-forming chamber.

3. In a molding apparatus a cylindrical core, a mold having an open-ended chamber and a neck-forming chamber opening at its lower end into the first chamber, the first chamber having a greater cross-sectional area than the second chamber, the top of the first chamber forming a shoulder surrounding the lower open end of the second chamber, said core located in the first chamber and adapted to be moved into the neck-forming chamber, the core having a base portion of greater diameter than the core, thereby providing a shoulder between the core and base member, a cylinder embracing the base and providing a slidable support for said base portion for centering the core in the mold, a ring slideable on the core, with the outer periphery slidably received by the wall of the open-ended chamber, a plurality of rods having the inner ends thereof secured to the ring and a coil spring surrounding each rod and located between the second shoulder and the under face of the ring, the upper face of the ring having an annular groove, the walls of which completing the mold for the neck-forming chamber, said coil springs adapted to be compressed when the core is moved into the neck-forming chamber for forcing the ring against the first-mentioned shoulder and cooperating with the core for closing the lower end of the neck-forming chamber.

RAYMOND A. SENKBEIL.
